(57) **CLAIM**

The ornamental design for a shoe sole, as shown and
described.

DESCRIPTION

FIG. 1 is a bottom plan view of a shoe sole showing my new
design;

FIG. 2 is a left side elevational view thereof;

FIG. 3 is a right side elevational view thereof;

FIG. 4 is a front elevational view thereof; and,

FIG. 5 is a rear elevational view thereof.

The broken line showing of a shoe upper in the Figures is
environmental only and forms no part of the design claimed.
